(57) **ABSTRACT**

A multiple position contoured body pillow having an elongated somewhat oblong or oval shape adapted to conform to the spine and upper torso of a human user by means of a main body section consisting of a longitudinally extending back portion having a contoured inner peripheral edge and a substantially straight outer peripheral edge, transversely extending symmetrically curved U-shaped arms attached to the ends of the main body section which arms may be repositioned toward the main body section and which arms are adapted to “spring back” into position when abducted from the main body section of the pillow, the first symmetrically curved arm being provided at a terminal end thereof with a pocket adapted to contain a foldable fabric pouch for storing remote controls, small books, and the like.

MULTIPLE POSITION SYMMETRICALLY CONTOURED BODY PILLOW

CROSS REFERENCE TO RELATED APPLICATION

This application is a continuation of U.S. Pat. No. 10/870,645, filed Jun. 17, 2004 now U.S. Pat. No. 7,114,206.

BACKGROUND OF THE INVENTION

1. Field of the Invention

The present invention relates to a body pillow. More particularly, the present invention involves a multiple position contoured body pillow having an elongated somewhat oblong or oval shape. The pillow has a longitudinally extending back portion having a contoured inner peripheral edge adapted to fit the spinal curvature of a user and a substantially straight outer peripheral edge. The pillow is further provided with transversely extending symmetrically curved U-shaped arms attached to the ends of the main body section, the arms being adjustable such that they may be repositioned in an inward (toward the main body section) conformation. Each arm is designed in such a way that it "springs back" into position if pulled away, or abducted, from the main body section of the pillow to create the sensation of snugness against the body of a user. The first symmetrically curved arm is provided at the terminal end thereof with a pocket adapted to contain a foldable fabric pouch for storing remote controls, small books, and the like.

2. Prior Art

There are a number of patents that show or relate to body support pillows. It is believed to be novel to provide a multiple position contoured body pillow with hinged arms adapted to support the body of a person in a secure position while the person is seated or lying down.

A preliminary patentability search was conducted on this invention and the following listed references were uncovered in the search.

Patent No.	Name	Date
Des. 201,492	Jacobson	Jun. 29, 1965
Des. 382,435	Schaffner, et al.	Aug. 19, 1997
Des. 409,038	Rojas, Jr., et al.	May 4, 1999
Des. 419,819	Bartoli	Feb. 1, 2000
Des. 420,845	Rumage	Feb. 22, 2000
Des. 431,745	Jackson	Oct. 10, 2000
Des. 453,653	Tunnell	Feb. 19, 2002
3,899,797	Gunst	Aug. 19, 1975
4,173,048	Varaney	Nov. 6, 1979
4,624,021	Hoffstetter	Nov. 25, 1986
4,901,384	Eary	Feb. 20, 1990
5,097,551	Smith	Mar. 24, 1992
5,987,674	Schaffner	Nov. 23, 1999
6,052,848	Kelly	Apr. 25, 2000
6,088,854	Brownrigg	Jul. 18, 2000
6,499,164	Leach	Dec. 31, 2002

The above patents are not considered to be particularly pertinent to the present invention.

The Jackson patent (Des. 431,745) discloses a head and body pillow with a pocket attached at the top corner of the pillow.

Gunst Pat. No. 3,899,797 discloses an inflatable member which is adjustable to create various configurations and is used as a structural component for a piece of furniture.

2

Varaney Pat. No. 4,173,048 discloses a pillow having a substantially "U" shape which can encircle a user. Varaney has a uniform thickness preventing the pillow from retaining a "folded" position.

5 Hoffstetter Pat. No. 4,624,021 discloses a contoured cushion adapted to fit the torso and between the legs of a user.

Smith Pat. No. 5,097,551 discloses a contoured pillow adapted to provide skeletal support.

Kelly Pat. No. 6,052,848 is a "U" shaped pillow adapted 10 to be positioned into a number of shapes to accommodate the user.

Leach Pat. No. 6,499,164 was issued to the present inventor and is a body pillow having a different shape than the present invention but a similar purpose.

SUMMARY OF THE INVENTION

The present invention involves a multiple position contoured body pillow comprising a longitudinally extending back portion having a contoured inner peripheral edge 20 adapted to fit the spinal curvature of a user, a substantially straight outer peripheral edge, the back portion having a first and second end, the first and second ends having transversely extending symmetrically curved arms attached thereto, the symmetrically curved arms having an inner peripheral edge and an outer peripheral edge, the point of attachment of the transversely extending symmetrically curved arms being flexible so as to permit adjustment thereof, the point of attachment of the transversely extending symmetrically curved arms being designed such that 30 they are resilient and spring back into their original position when pulled away, or abducted, from their original resting position so as to provide a "hinge" type movement or mild resistance of the arms for purposes of securing the body of 35 a person utilizing the pillow without requiring the person to manually adjust the arms, the mild resistance feature further facilitating the maintenance of ideal positioning of the pillow for the desired body support, the transversely extending symmetrically curved arms being curved in a substantially "U" shape and forming a well along the interior 40 curvature of each arm at its inner peripheral edge, the inner peripheral edge of each symmetrically curved arm being provided with a contoured portion adapted to conform to the body structure of a human user, the contoured portion 45 expanding into a substantially straight portion which extends to the terminal end of each arm, the two symmetrically curved arms being of sufficient length that each arm contacts the other arm at the terminal ends thereof to form a complete substantially oblong or oval shape, and the first 50 symmetrically curved arm being provided at the terminal end thereof with a pocket adapted to contain a foldable fabric pouch for storing remote controls, small books, and the like.

55 BRIEF DESCRIPTION OF THE DRAWINGS

FIG. 1 is a perspective view showing the body pillow of the present invention laid out in a flat position.

FIG. 2 is a front view showing the body pillow of the present invention folded over onto itself to create optimal back support for the user (not shown) in a seated position.

FIG. 3 is a rear view of the body pillow of the present invention showing the pillow conforming to the spine of a user lying on her side with her back resting against the longitudinally extending back portion of the pillow.

65 FIG. 4 is a rear view of the body pillow of the present invention showing the pillow conforming to the front torso

region of a user lying on her side with her upper body resting against the longitudinally extending back portion of the pillow.

FIG. 5 is a front view of the body pillow of the present invention showing the transversely extending symmetrically curved arms brought to rest against each other, each transversely extending symmetrically curved arm being folded over and resting against the longitudinally extending back portion of the pillow.

FIG. 6 is an alternative view similar to FIG. 2 showing a foldable fabric pouch attached to a terminal end of the first transversely extending symmetrically curved arm for storing remote controls, portable or cellular telephones, and the like.

FIG. 7 is a perspective view showing a user demonstrating the "hinge" type movement of the arms for purposes of adjustability.

DETAILED DESCRIPTION OF THE PREFERRED EMBODIMENTS

Referring to the drawings in detail, FIG. 1 shows a multiple position contoured body pillow 10 laid out in a flattened or resting position, the body pillow 10 comprising an elongate back portion 12 having a length of not less than thirty inches (30") and consisting of a substantially straight outer edge or outer perimeter 18 and a contoured inner edge or perimeter defining a bulge 20, the back portion 12 narrowing at two points 26 where the back portion 12 transitions into symmetrically curved arms 14 and 16, each symmetrically curved arm 14 and 16 comprising an outer U-shaped portion 22 and an inner well 24, the symmetrically curved arms terminating at ends 28 and 30. In this position, the terminal ends 28 and 30 of the symmetrically curved arms 14 and 16 of the body pillow 10.

FIG. 2 shows the body pillow 10 in an alternate position of the body pillow 10 where the body pillow 10 has been folded in half to form a "double decker" or stacked support. This position is achieved by folding the body pillow 10 at the mid-section (not numbered) of the back portion 12 and stacking one symmetrical end comprising half of the back portion 12, the U-shaped portion 22 and the arm 16 (or 14 if the pillow were reversed) such that there is alignment between the wells 24 of each arm 14 and 16 and the terminal ends 28 and 30 of the body pillow 10. In this position, a human user (not shown in this Figure) sitting in an upright or semi-upright position would receive the wells 24 of the body pillow 10 around her middle and lower back with one arm resting on the symmetrically contoured arm 16 and the opposite arm resting on the topmost section of the back portion 12, the mild resistance feature would create tension between the folded back portion 12 and the arms 14 and 16, causing the arms to be effectively pulled toward, or adducted toward, the folded back portion 12 to surround the body of the human user (not shown).

FIG. 3 shows the body pillow 10 of the present invention laid out in a position similar to that shown in FIG. 1, but with the addition of a human user 38 laying on her side. In this position, the head 40 of the user 38 is received against one of the U-shaped portions 22 with the neck and shoulder area (not numbered) of the user 38 resting along the well 24 of the body pillow 10, the opposite U-shaped portion 22 and the arm 16 are received between the legs 46 of the user 38, the contoured inner portion 20 of the back portion 12 corresponds to the curvature of the spine 44 of the user 38, while the arm 14 corresponds to the front torso (not num-

bered) of the user 38 and the arm 14 of the body pillow 10 is received between the arms 42 of the user 38. In this position, the terminal ends 28 and 30 of the arms 14 and 16, respectively, are brought together to form a complete enclosure around the body of the user 38 to create a feeling of security and aid in maintaining the desired position of the user 38.

FIG. 4 is a view similar to FIG. 3, but shows the human user 38 turned in the opposite direction to that shown in FIG. 10. 3. In this position, the head 40 of the user 38 is received against one of the U-shaped portions 22 with the neck and shoulder area (not numbered) of the user 38 resting along the well 24 of the body pillow 10, the opposite U-shaped portion 22 is received between the legs 46 of the user 38, the 15 contoured inner portion 20 of the back portion 12 corresponds to the front upper torso (not numbered) of the user 38, while the arm 14 and the terminal ends 28 and 30 correspond to the spinal curvature 44 of the user 38 and the back portion 12 of the body pillow 10 is received between the 20 arms 42 of the user 38. In this position, as indicated in FIG. 3, the terminal ends 28 and 30 of the arms 14 and 16, respectively, are brought together to form a complete enclosure around the body of the user 38 to create a feeling of security and aid in maintaining the desired position of the 25 user 38.

FIG. 5 shows the body pillow 10 of the present invention in a second folded position whereby the back portion 12 of the body pillow 10 rests against a floor, bed, or other surface (not shown), the U-shaped portions 22 are moved inwardly 30 with respect to the back portion 12 and the arms 14 and 16 are brought together in an upward position with the terminal ends 28 and 30 of the arms 14 and 16 bearing against each other to create a raised central section. In this embodiment, a user (not shown) will sit or lay with her back (or, alternatively, her stomach) against the arms 14 and 16 with her head resting against the terminal ends 28 and 30 and her arms may rest on the U-shaped portions 22.

FIG. 6 shows the body pillow 10 of the present invention folded into a position similar to the position shown in FIG. 40. 2 with the addition of a foldable pocket 32 which may be 40 stitched into the seam 36 of the terminal end 28 (or 30, not shown) of the body pillow 10 for the purpose of holding 45 small items such as a remote control 34 or portable telephone (not numbered). The covering material (not numbered) of the arm 14 (or 16, not shown) is provided with a section of overlapping or additional material 48 which is adapted to receive the foldable pocket 32 when the foldable pocket 32 is not in use.

FIG. 7 shows the body pillow 10 of the present invention 50 laid out in a substantially flat position with a user 38 abducting the arm 14 of the body pillow 10 from the contoured inner portion 20 of the back portion 14 creating a 55 mild resistance between the contoured inner portion 20 and the arm 14. Once the arm 14 is released by the user 38, the mild resistance will cause the arm 14 to be adducted toward the contoured inner portion 20 (in a manner similar to spring action), restoring the body pillow 10 to its original shape.

What is claimed is:

1. A multiple position contoured body pillow for a user, 60 the pillow formed of a resilient, shape-sustaining material and comprising, in its resting position, an elongate back portion having opposing ends and a pair of opposing U-shaped arms, one extending from each of the ends of the back portion, wherein the back portion includes a contoured inner perimeter defining a bulge, the bulge being shaped and positioned alternately to support the user's spine or abdomen when the user's body is positioned lengthwise along the 65

5

inner perimeter of the back portion, wherein each of the arms has an inner perimeter forming an inner well sized to receive alternately the upper or lower torso of the user, the inner perimeter of each of the arms being continuous with the inner perimeter of the back portion, and wherein each of the arms terminates in a terminal end.

2. The pillow of claim 1 wherein the arms are symmetrical when the pillow is in the resting position.

3. The pillow of claim 2 wherein the terminal ends of the arms are generally adjacent the bulge and each other when the pillow is in the resting position.

4. The pillow of claim 1 wherein the back portion is foldable so that one of the arms is stacked on top of the other with their inner wells aligned.

5. The pillow of claim 1 wherein the pillow is sized for an average adult female.

15

6

6. The pillow of claim 1 wherein the pillow comprises a fabric pouch.

7. The pillow of claim 6 wherein the fabric pouch is positioned on the terminal end of one of the opposing arms.

8. The pillow of claim 1 wherein the back portion of the pillow further comprises an outer perimeter that is straight.

9. The pillow of claim 8 wherein each of the arms further comprises an outer perimeter that is curved.

10. The pillow of claim 1 wherein each of the arms further comprises an outer perimeter that is curved.

11. The pillow of claim 1 wherein the terminal ends of the arms are generally adjacent the bulge and each other when the pillow is in the resting position.
